DISPLAY BAG FOR MERCHANDISE OR THE LIKE

Israel Corbe, 37 Central Mall, Brooklyn, N.Y.

Filed Aug. 6, 1959, Ser. No. 57,081

Term of patent 14 years

(Cl. D58—2)

FIG.1

2 ←

2 ←

The rear of the article not shown is substantially like the front.

I claim:

The ornamental design for a display bag for merchandise or the like, substantially as shown and described.
